(57) **CLAIM**

The ornamental design for a combined shroud and handle for a gas cylinder, as shown and described.

DESCRIPTION

FIG. 1 is a top, front and right side perspective view of a combined shroud and handle for a gas cylinder, showing our new design;

FIG. 2 is a top, front and left side perspective view thereof;

FIG. 3 is a front plan view thereof;

FIG. 4 is a rear plan view thereof;

FIG. 5 is a right side plan view thereof;

FIG. 6 is a left side plan view thereof;

FIG. 7 is a top plan view thereof;

FIG. 8 is a bottom plan view thereof;

FIG. 9 is a top, front and right side perspective view of a combined shroud and handle for a gas cylinder, showing our new design in an illustrative environment;

FIG. 10 is a top, front and left side perspective view thereof;

FIG. 11 is a front plan view thereof;

FIG. 12 is a rear plan view thereof;

FIG. 13 is a right side plan view thereof; and,

FIG. 14 is a left side plan view thereof.

The broken lines showing a portion of a gas cylinder and apparatus associated with the gas cylinder are for the purposes of illustrating environment and form no part of the claimed design.
